(74) *Attorney, Agent, or Firm* — Foley & Lardner LLP

(57) **CLAIM**

The ornamental design for a pliers as shown and described.

DESCRIPTION

FIG. 1 is a front perspective view from above of the claimed pliers according to one embodiment.

FIG. 2 is a rear perspective view from below of the claimed design of FIG. 1;

FIG. 3 is a top view of the claimed design of FIG. 1;

FIG. 4 is a bottom view of the claimed design of FIG. 1;

FIG. 5 is a front view of the claimed design of FIG. 1;

FIG. 6 is a rear view of the claimed design of FIG. 1;

FIG. 7 is a right-side view of the claimed design of FIG. 1; and

FIG. 8 is a rear side view of the claimed design of FIG. 1.

FIG. 9 is a front perspective view from above of the claimed pliers according to another embodiment;

FIG. 10 is a rear perspective view from below of the claimed design of FIG. 9;

FIG. 11 is a top view of the claimed design of FIG. 9;

FIG. 12 is a bottom view of the claimed design of FIG. 9;

FIG. 13 is a front view of the claimed design of FIG. 9;

FIG. 14 is a rear view of the claimed design of FIG. 9;

FIG. 15 is a right-side view of the claimed design of FIG. 9; and,

FIG. 16 is a rear side view of the claimed design of FIG. 9.

Any portion of the article depicted in broken lines forms no part of the claimed design. Broken lines formed by equal length dashes show unclaimed portions of the design. Broken lines formed of unequal length dashes (i.e., dash-dot) show boundaries between claimed and unclaimed portions of the design.

1 Claim, 12 Drawing Sheets
